UNITED STATES PATENT OFFICE.

MICHAEL W. ROBICHAUD, OF SEATTLE, WASHINGTON.

ORNAMENTAL TOY DOLL.

Application filed January 22, 1927. Serial No. 162,854.

This invention relates to dolls, and particularly to a doll made in several sections for use as a toy or ornament for automobiles, or for attracting attention in public places.

The object of the invention is to provide a simple and easily constructed doll, with the upper portion of the body, and the legs rigidly connected in an upright position, with the abdominal portion of the body suspended from the upper portion thereof by means of a thin rubber or elastic fabric surrounded by tasseled cords, to resemble the dress of a Hawaiian hula hula dancer, with a space between the upper portion of the body and the abdominal section, and a space between the legs and the abdominal section, and the abdominal section held in a suspended position between the upper portion of the body and legs by means of the elastic skirt which is attached to both the upper portion of the body and the abdominal section, with the tasseled cords or fringe hanging below the skirt.

A further object of the invention is to provide an ornament for an automobile radiator cap, or other moving object, the ornament in form of a doll, with the upper portion thereof rigidly attached to the legs by rods connecting the same with a suitable space between the fixed portions, for a hollow abdominal section of the doll to be movably suspended from the upper section by an elastic band with a fringed skirt connected to the abdominal section, the arrangement of the whole to resemble an Indian dancer, and when the doll is moved, as on an automobile on the street, the abdominal section will rise and fall, raising and lowering the fringe, portraying the appearance of a living dancer in the Indian dance, or "shimmy".

The invention is further illustrated by the accompanying drawings, of which

Figure 1 represents a front elevation of the doll.

Figure 2 represents a side elevation thereof in section.

Like numerals on the different figures represent like parts.

1 represents the upper portion of the doll with head and arms in any desired position, the legs 2 forming the lower portion or section of the body, with rods 3 attached to the upper and lower section and extending between the same, and holding the fixed por-

tions at a suitable space apart from the free mounting of the central or abdominal section 4 of the body, the upper and lower sections are preferably solid, for providing secure attachment for the rods, while the central section is hollow, to fit around the rods, and is connected to and suspended from the upper section by a rubber or elastic band 5, which fits snugly around the upper section and the middle section with the upper edge turned down as a fold 6 over reinforcing elastic bands 7.

The middle portion 4 is shorter than the distance between the upper and lower section leaving spaces 8 above and below so that the middle portion has play and room to move up and down between the fixed portions 1 and 2. A skirt preferably of fringe as 10 is attached to the middle or abdominal section, by means of elastic bands 11 or other suitable means, and serves to further emphasize the movements of the central section when the doll is moved, and also resembles the grasses or similar forms of loose coverings used by Indian dancers.

In use the doll may be mounted on an automobile radiator cap, or other position on an automobile or other movable object, and when the doll is moved thereby, the middle portion, being suspended on the elastic band, will vibrate in swaying and rising and falling motions, and thereby moving the skirt in similar ways, and producing the effect of a human dancer.

My invention is not limited to elastic band connection but covers any resilient connections for holding the central section in the space between the fixed portions to permit a tremulous motion, as by coil springs which may be mounted within the middle section and attached thereto and also attached to one or both of the fixed sections.

Having described my invention, I claim:

1. An ornamental doll comprising, an upper section, leg portions, rods connecting the upper section and leg portions together, an abdominal section movably arranged between the upper section and leg portions, the abdominal section being in tubular form for fitting around the rods and arranged in spaced relationship to the upper section and leg portions, an elastic band attached to said upper section and to said abdominal section to thereby suspend the latter, a fringed skirt attached to the abdominal section, the lower

edge extending a suitable distance below the abdominal section.

2. An ornamental toy doll comprising, an upper and lower section rods attached to said upper section and lower section to thereby rigidly connect the sections, a central tubular section formed to extend loosely around the rods, the central section being arranged in spaced relationship to the upper and lower sections to allow for movement therebetween, an elastic band connecting the upper and central sections adapted to hold the central section suspended above the lower section, a

skirt attached to the central section and suspended therefrom a suitable distance. ¹⁵

3. A toy or the like comprising a suitable upright figure having supporting leg portions, an abdominal portion and a head and chest portion, the latter rigidly secured to the leg portion, the abdominal portion ²⁰ spaced from both the other portions and suspended from the head and chest portion for swinging movement relatively to both said other portions.

In testimony whereof I affix my signature.
MICHAEL W. ROBICHAUD.
